United States Patent Office.

EDWARD A. SMITH, OF ST. ALBANS, VERMONT, ASSIGNOR TO HIMSELF AND JOHN W. NEWTON.

Letters Patent No. 75,306, dated March 10, 1868.

IMPROVEMENT IN SEATS FOR HARVESTERS.

The Schedule referred to in these Letters Patent and making part of the same.

TO ALL WHOM IT MAY CONCERN:

Be it known that I, EDWARD A. SMITH, of St. Albans, in the State of Vermont, have invented and made a certain new and useful Improvement in Seats for Mowing and Reaping-Machines; and I do hereby declare the following to be a full, clear, and exact description of the said invention, reference being had to the annexed drawing, making part of this specification, wherein—

Figure 1 is an inverted plan of the seat-supporter, and

Figure 2 is a vertical section of the seat and supporter.

Similar letters denote the same parts.

The seats of mowing and reaping-machines are usually very uncomfortable for the rider, in consequence of the same being more or less rigid, and receiving the jar and tremor of the machine as it rolls upon the ribbed wheels and over uneven surfaces.

The nature of my said invention consists in a seat for mowers and reapers, formed with helical springs introduced between the seat and the supporting-bar, the ends of said springs being received in sockets on the respective parts, and the seat and bar being held together by a screw-link that allows the parts to move freely, but prevents them from separating when in use. By this construction a cheap, easy, strong, and reliable seat is obtained, and one that has a free vertical and lateral motion, thus relieving the driver from the unpleasant jar usual in the seats heretofore employed.

In the drawing, *a* represents the seat-supporter, formed at one end with a foot, *b*, to be attached to the reaper or mower, and at the other end with the flange *c*, that receives the crown-plate *d*, upon which are sockets *e*, for the springs *f*, standing around in a circular range. *g* is the seat, of a suitable size and shape, with sockets *h* upon the under side, for the upper ends of the springs *f*. A screw-link, *i*, connects the seat *g* with the supporter-flange *c*. The hole through which such link passes is sufficiently large to allow the parts to move freely as the seat-springs yield to concussion or pressure.

What I claim, and desire to secure by Letters Patent, is—

The seat for mowers or reapers, formed with sockets on the under side of the seat, receiving helical or spiral springs, in combination with the sockets on the crown-piece or seat-supporter, and with the connecting-link *i*, substantially as and for the purposes set forth.

In witness whereof, I have hereunto set my signature, this fifteenth day of November, A. D. 1867.

E. A. SMITH
